UNITED STATES PATENT OFFICE

MORRIS C. ANDERSON, OF MARLIN, TEXAS

SLOGAN APPARATUS OR ADVERTISING DEVICE

Application filed July 18, 1930. Serial No. 468,926.

This invention relates to a slogan apparatus or advertising device which is driven by a liquid motor in a rotary manner so that the various slogans or advertisements thereon will be successively brought into view and held for periods sufficient for an observer to read the various slogans during their rest intervals.

More specifically, the invention relates to a rotatable illuminated cylinder adapted to carry signs or slogans and which is actuated by a water motor comprising a wheel having water containers and floats therein, the rotary movement of the motor being automatically stopped by a catch engageable by float arms at definite intervals.

The drawings show a preferred embodiment of the device, wherein

Figure 1 is a view in elevation of the apparatus showing a slogan during a rest interval and showing a portion of the outer casing cut away;

Figure 2 is a view in sectional elevation showing the various parts of the apparatus;

Figure 3 is a fragmentary portion of an end of the cylindrical device shown in Figure 2;

Figure 4 is a vertical section taken on the line 4—4 of Figure 2, showing the arrangement of water containers, float arms, etc.;

Figure 5 is a vertical section taken on the line 5—5 of Figure 2 of a portion of the cylindrical display holding device;

Figure 6 is a view in elevation of the cylindrical display holder showing means for securing a slogan bearing member thereto and the construction of the side casing members of the same;

Figure 7 is a view in end elevation of the device shown in Figure 6;

Figure 8 is a view showing the details of the spring stop mechanism and the catch engageable with the float arms;

Figure 9 is a view taken along the line 9—9 of Figure 8;

Figure 10 is a view showing the range of movement of a float arm before and after its engagement with the catch mechanism; and

Figure 11 is a perspective view of one of the water containers.

Referring to the drawings, A designates a substantially cylindrical casing having an inwardly turned flange at each of its ends and an opening 2 in its wall. End members B and C are secured to the ends of the casing A, as by means of bolts D passing through said end members and the flanges of the casing. The casing A is secured, as by bolts 4, to a base 3 which forms a trough for a purpose to appear hereinafter.

A partition 5 in the casing A adjacent one end of the latter divides said casing into a pair of chambers 6 and 7 in which a water motor and a cylindrical sign carrier are respectively rotatable.

The water motor comprises a wheel element 8 having its hub 9 secured to a shaft 10 which extends longitudinally of the casing A. The wheel element 8 carries adjacent its periphery a plurality of box-like containers 11, one at the outer end of each spoke of said wheel element. Each of the containers 11 comprises a bottom, front and side walls and an overhanging hood. A lip 12, of which the purpose will appear later, projects forwardly from the upper edge of the front wall of each container and a flange 13 is carried by the rear wall thereof by means of which the container is secured, as by bolts or rivets, to the wheel element 8.

A float-carrying lever 14 is fulcrumed as at 15 on the wheel element 8 adjacent each of the containers 11 and has the end of one of its arms bent toward the periphery of the wheel element 8 to form a catch-portion and has the end 17 of its other arm connected to a float 18 in the adjacent container 11. The combined weight of the arm 17 of each lever 14 and the float 18 carried thereby is greater than the weight of the other arm of such lever, so that, when one of the container elements 11 is empty and it and its associated lever 14 are positioned above the shaft 10, as shown in Figure 4, the catch portion 16 of such lever will be elevated to engage the lug 24 carried by the partition 5 and to be described later. The arm of the lever 14 on which the catch portion 16 is formed extends between a pair of stops 19 carried by the rim of the wheel element 8. Thus the rocking

movement of the lever 14 is limited in each direction.

Means are provided for periodically arresting the rotation of the wheel element 8, the means shown for this purpose being of the following construction:

10 A stud 20, secured to the partition 5, as by a nut 21, on one side of a vertical plane passing through the axis of the shaft 10, extends toward the wheel element 8 and carries a stop 22 which projects radially therefrom. A sleeve 23, mounted to rock on said stud, has a lug 24 extending radially therefrom to engage the stop 22 when the stud 23 is rocked 15 in one direction. The lug 24 of the sleeve 23 is normally held in engagement with the stop 22 by a spring 25 surrounding the stud 20 and having its opposite ends connected, respectively, to the partition 5 and sleeve 23.

20 A display holding cylinder is secured to the shaft 10 in the chamber 7, the shaft being rotatable in bearings 26 carried by suitable supports 27 rising from the bottom of the base member 3. An electric lamp 28 is supported by the partition 5 within the chamber 7, and a second electric lamp 29, also in the chamber 7, is carried by the support 27 at the right-hand end of said chamber. Both of said lamps are connected to suitable leads for 25 current supply.

The display holding cylinder comprises a sleeve S mounted on the shaft 10 and secured to the latter, as by a set-screw T, and a pair of cage-like members carried by said sleeve S, each of which members comprises a plurality of strips 30 extending radially from the sleeve S and then substantially parallel to the shaft 10 and connected at their outer ends by an annular strip 30'. The parts of 30 the strips 30 which extend parallel to the shaft 10 have substantially T-shaped portions 31 projecting from their outer faces and the horizontal parts or flanges of the T-shaped portions 31 which project from 40 longitudinally aligned parts of the strips 30 of the two cage-like members are connected together to bridge the space between said members and unite said members. Thus a groove is formed in each of the longitudinal 45 edges of the strips 30, forming inner and outer flanges, as shown in Fig. 5, and translucent signs 32 are mounted between adjacent strips 30 with their opposite edges removably inserted in the longitudinal 50 grooves of said strips. A clip 33 carried by and extending beyond the end of each of a diametrically disposed pair of the strips 30 of each of said cage-like members projects through a slot formed in an end plate 34, and the ends of said clips are bent to 60 overlie the outer face of their associated end plates 34 and thus detachably secure said end plates to said cage-like members. The end plates 34 also have ears 35 on their peripheries, which ears overlie the ends of the

strips 30 and the corners of the signs 32, the ends of the outer flanges being cut away for this purpose as shown in Fig. 2. A pipe 38 (Figures 2 and 10) extending through the end member B of the outer casing on the opposite side of a vertical plane passing through the axis of the shaft 10 from the stud 20 has a spout directed downwardly into the chamber 6 to deliver water or other fluid upon the lips 12 of the containers 11 and into said containers as such containers, in the rotation of the wheel element 8, pass under such spout. The rate of flow of water through the pipe 38 may be regulated by any suitable means, such as a valve (not shown).

The operation of the apparatus is as follows:

Assuming that the containers 11 are empty, and one of same is below the spout with the catch engaging portion 16 of its float carrying lever 14 in engagement with the end of the lug 24, water is permitted to flow through the pipe 38 and its spout upon the lip 12 of such container 11 and thence into the container to fill the container and cause the float 18 therein to rise. As the float rises it will rock the lever 14 on its pivot to disengage the catch engaging portion 16 thereof from the lug 24, and, since said container is at one side of a plane passing vertically through the axis of the shaft 10, the weight of the water in said container will cause the wheel element 8 to move in a clockwise direction (Figure 4) until the next succeeding container arrives below the spout, at which time the catch engaging portion 16 of the lever 14 associated with the latter chamber will engage the lug 24 and thus arrest further movement of the wheel element 8 until such chamber is filled with water or other liquid from the spout. During this period one of the translucent signs 32 carried by the display holding cylinder will be displayed through the opening 2 in the casting A. When said second chamber 11 is filled with water or other liquid its float 18 will rise and release the catch 16 of its associated lever 14 from the lug 24 so that the weight of the liquid in the first and second containers will cause the display-holding cylinder to turn further in a clockwise direction until the catch 16 of the lever 14 associated with the third container engages the lug 24, whereupon movement of the display-holding cylinder will be again arrested until the third container 11 is filled with liquid to release its catch 14 from the lug 24, during which period the second sign carried by the display-holding cylinder will be presented to view through the opening 2 of the cylinder A. The operation just described will be repeated so long as liquid flows from the spout. As the first and second containers move into the positions in which the two containers at the right of the shaft 10 are shown in Figure 4, 125 130

the liquid in such containers will be prevented by their hoods 12' from flowing out of same. But as each container passes directly below the shaft 10 the liquid therein will be poured out therefrom so that the containers will be empty as they approach and pass under the lug 24 and their catches 16 will be positioned to engage said lug.

As the catch 16 of each lever 14 engages with the lug 24 the impact of such catch against said lug will rock said lug and the sleeve 23 by which it is carried on the stud 20 against the resistance of the spring 25, thus cushioning such impact, after which the spring 25 will return the lug 24 to its normal position against the stop 22 and thus cause the sign which is at that time behind the opening 2 of the casing A to be presented to view in proper position through said opening.

While it is preferred to employ the specific construction and arrangement of parts shown and described, it is to be understood that such construction and arrangement is not essential except so far as specified in the appended claims and that it may be changed or modified without departing from the invention.

What I claim, is:

1. An advertising device comprising a casing having a sight opening, a rotatable shaft supported in the casing, a wheel mounted on the shaft and having means for carrying advertising matter to be viewed thru said sight opening when the advertising matter is in alignment therewith, a second wheel mounted on the shaft, water containers on the second-named wheel, float arms pivotally mounted on the second-named wheel adjacent said containers, and catch means supported in the casing and engageable with the float arms to periodically arrest the first-named wheel.

2. A slogan apparatus comprising a base member, a substantially cylindrical casing mounted thereon and having a sight opening, a vertical partition in said casing defining a water wheel chamber and a display wheel chamber, standards mounted in the display wheel chamber and supporting a rotatable shaft, a display wheel mounted on the shaft, means within the display wheel and supported by the standards to illuminate the interior of the display wheel chamber, a water wheel mounted on the shaft in the water wheel chamber adjacent to the display wheel, water buckets on the water wheel, float arms associated with the buckets and pivotally mounted on the water wheel, float means carried by the float arms and operable in the water buckets, stops mounted on the water wheel adjacent the float arms to limit their pivotal rotation, catch means secured to the partition and engageable with the float arms, a spring attached at one end to the partition and at the other end to the

catch means, a stop associated with the catch means to limit its movement in one direction, and means to drip water into the water buckets to rotate the water wheel and display wheel.

3. In an advertising device, a base member, a casing mounted on the base member, a vertical partition in the casing defining a display wheel chamber and a water wheel chamber, a shaft horizontally mounted to extend in both chambers, a display wheel mounted on that part of the shaft in the display wheel chamber, a water wheel mounted on that part of the shaft in the water wheel chamber, and means associated with the water wheel to rotate both wheels and to arrest the same at predetermined intervals.

4. In a machine of the class described, a base member, a casing mounted on the base member, a vertical partition in the casing defining a display wheel chamber and a water wheel chamber, that part of the casing which forms the display wheel chamber having a sight opening in its wall, a shaft horizontally mounted to extend in both chambers thru the partition, a display wheel mounted on the shaft in the display wheel chamber and adapted to bear a slogan to be viewed thru the sight opening, a water wheel mounted on the shaft in the water wheel chamber, and means associated with the water wheel to rotate both wheels and to arrest the same at predetermined intervals.

5. A machine of the class described, comprising a casing having a sight opening in its wall, a display carrying wheel rotatable in said casing past said sight opening, illuminating means in said wheel, and means for imparting rotation to said wheel, said means including a second wheel in said casing concentric and rotatable with the first-named wheel, a plurality of water buckets mounted on said second wheel, and water supply means above the axis of rotation of said second wheel for filling said buckets in succession.

6. In a display device, a rotary supporting cage comprising end pieces, spaced longitudinal bars connected to said end pieces, and longitudinal bars, T-shaped in cross-section, secured to said first-named bars, the flanges of the T-bars forming with the first-named bars grooves for the reception of display sheets.

7. In a display device, a cage comprising a central support, end pieces spaced from said support, arms radiating from said support, longitudinal bars extending from said arms to said ends, and means connecting the ends of said bars to the end pieces.

8. In a display device, a cage comprising a central support, end pieces spaced from said support, arms radiating from said support, longitudinal bars extending from said arms to said end pieces, said end pieces having

openings, and tongues on the ends of the bars extending through said openings and bent over on the opposite sides of the end pieces.

9. In a display device, a rotary supporting cage comprising end pieces, spaced longitudinal bars connected to said end pieces, additional longitudinal bars, T-shaped in cross-section, secured to said first-named bars, the first-named bars forming with the flanges of the T-bars grooves for the reception of display sheets, the outer flanges of the T-shaped bars being cut away at their ends, and projections on the end pieces extending over the portions of said bars from which the outer flanges have been cut away.

10. A device of the class described, comprising a rotatable display device, a water wheel connected thereto, water supply means above the axis of rotation of said water wheel, buckets on said wheel to successively receive water from said water supply means, means for arresting said wheel while each bucket is being filled, and means including a float in each bucket operative when the water in such bucket reaches a pre-determined level to release said wheel arresting means.

11. A device of the class described, comprising a rotatable display device, a water wheel connected thereto, buckets on said wheel, means for arresting said wheel when the successive buckets reach a predetermined point, said means comprising a detent and catches associated, respectively, with said buckets and engageable with said detent, means for filling each bucket as it reaches said point, and a float in each bucket operative to release the catch associated therewith from said detent when the bucket is full.

12. A device of the class described, comprising a rotatable display device, a water wheel connected thereto, buckets on said wheel, means for arresting said wheel as the successive buckets reach a predetermined point, means for filling each bucket as it reaches said point, and float-operated means for releasing the wheel when the bucket is full.

In testimony whereof I have hereunto set
50 my hand.

MORRIS C. ANDERSON.
